(57) **CLAIM**

The ornamental design for a liquid applicator for medical use as shown and described.

DESCRIPTION

1. Liquid applicator for medical use

Figure 1.1 is a right side view of a liquid applicator for medical use showing the handle in a first position of use; Figure 1.2 is a top view thereof;

Figure 1.3 is a bottom view thereof;

Figure 1.4 is a front view thereof;

Figure 1.5 is a back view thereof;

Figure 1.6 is a perspective view thereof; and

Figure 1.7 is a right view thereof showing the handle in a second position of use.

The left side view is a mirror image of the right side view.
